CHAIR

Charles L. Pettibone, Shaker Heights, Ohio, assignor to The B. L. Marble Chair Company, Bedford, Ohio, a corporation of Ohio

Application March 30, 1954, Serial No. 29,778

Term of patent 14 years

(Cl. D15—1)

Fig. 1

To all whom it may concern:

Be it known that I, Charles L. Pettibone, a citizen of the United States, residing at Shaker Heights, county of Cuyahoga, State of Ohio, have invented a new, original, and ornamental Design for a Chair, of which the following is a specification, reference being made to the accompanying drawings, forming a part hereof.

In the drawings:

Fig. 1 is a perspective view taken generally from the front of the chair showing my new design; and,

Fig. 2 is a perspective view taken generally from the side of the chair.

I claim:

The ornamental design for a chair, as shown.
